UNITED STATES PATENT OFFICE.

ISAAC S. PURCELL, OF OAK PARK, ILLINOIS, ASSIGNOR TO TENTOBED COMPANY, OF CHICAGO, ILLINOIS, A CORPORATION OF ILLINOIS.

COT.

1,394,578.

Specification of Letters Patent. Patented Oct. 25, 1921.

Application filed May 8, 1919. Serial No. 295,687.

To all whom it may concern:

Be it known that I, ISAAC S. PURCELL, citizen of the United States, residing at Oak Park, in the county of Cook and State of Illinois, have invented certain new and useful Improvements in a Cot; and I do hereby declare the following to be a full, clear, and exact description of the invention, such as will enable others skilled in the art to which it appertains to make and use the same.

My invention relates to folding cots, and in one of its general aspects aims to provide an effective air jacket below the bed of the cot, thereby avoiding the necessity of using heavy and bulky padding to insure comfort to the occupants of the cot. In another aspect, my invention relates to folding cots of a type particularly suitable for use in automobiles, and aims to provide simple means for rigidly supporting a cot with the bed stretched above the seats and without having any of the supporting parts engaged with the cushioning of the seats; also, to provide simple, effective, and easily operated means for tensioning the bed of such a cot. Furthermore, my invention aims to provide a folding cot in which the legs can be compactly folded close to the end rails, to provide a cot which can easily be erected within an automobile, and to provide an air-jacketing member below the bed of the cot which will also afford a weather-proof housing for the cot bed and for the major portions of the end rails when the cot is rolled up into a compact bundle. Furthermore, my invention aims to provide a folding cot of the class described, in which the straps used for securing the cot in operative position will also serve for securing the rolled up cot in its compacted form, and in which the straps will serve this purpose while continuously attached to the end rails of the cot. My invention also aims to provide simple means for effectively stiffening the end rails of the cot, to provide a simple and effective hinge for securing each leg to one of the end rails, and to provide effective means for simultaneously securing both the hinges and the straps to the end rails. Still further objects will appear from the following specification and from the accompanying drawings, in which—

Figure 1 is a side elevation showing the cot of my invention as installed for use in an automobile.

Fig. 2 is a slightly enlarged view of the same cot compacted into a bundle.

Fig. 3 is an end view of the cot, with the tensioning straps omitted, showing the legs both in their extreme raised positions and 60 in an intermediate position, and also showing one of the legs folded close to the adjacent end rail.

Fig. 4 is a bottom view of one of the end rails, showing how the legs fold against the 65 latter.

Fig. 5 is an enlarged transverse section through the bed of the cot and the wrapping member which affords the air jacket under the bed.

Fig. 6 is an enlarged and fragmentary section through one of the end rails, showing the method of stiffening the latter.

Fig. 7 is an enlarged transverse section through one of the end rails, showing the 75 connection of the latter with the hinge carrying the leg and with one of the tensioning straps.

In the embodiment of the drawings, the subject of my invention includes a bed-bottom 1 stretched between a pair of end rails 2 and 3, each of which end rails is supported by a pair of legs hinged to the same. One pair of the legs, namely the one intended for the rear of the car, is desirably 80 made of such length as to set upon the rear seat of the car when the cushion is removed from the latter, as shown at 4 in Fig. 1. The corresponding forward legs 5 are desirably longer than the rear legs 4, so that 85 they may reach the floor of the car in front of the front seat. To tension the bed of the cot and to keep the legs from swaying longitudinally of the car, I provide pairs of straps 6 and 7 for connecting the rear 90 and forward end rails with rigid parts of the automobile. For example, the rear straps 6 may desirably be looped over the socalled rest irons 8 as shown in Fig. 1, while the forward straps 7 may lead to the support 100 for the bow. In each case, I desirably provide each strap in the form of an endless loop having suitable means for adjusting its length, and desirably pass each strap through the eye of a swivel bolt 9, extending 105 through one of the end rails near an end of the latter. The shank of this pivot bolt desirably also acts as a swivel for a pair of angle plates 10 disposed at opposite sides of the end rail (as show in Fig. 7) and riv- 110

eted or bolted to the upper end of the adjacent leg. When in use, each of the bolts 9 is disposed with its shank extending horizontally and lengthwise of the cot, thus 5 affording a pivot upon which the angle plates 10 can be swung to move the leg carried thereby into any desired position ranging from the vertical position shown in full lines in Fig. 3 to a position contiguous 10 to the under side of the adjacent end rail, as also shown for one leg in dotted lines in the same figure. Consequently, by moving the legs to positions more and more closely approaching the extreme vertical position, 15 the end rail can be raised, thereby coöperating with the straps 6 and 7 in tensioning the bed of the cot.

To prevent the tips of the legs from slipping on the floor of the car, or on the seat, 20 I desirably equip the free end of each leg with a projecting tip. I also desirably taper the legs and overlap them as shown in Fig. 4, so that they will fold alongside each other underneath the adjacent end rail and into 25 a width closely approximating the width of the end rail. To stiffen the end rails against the strains to which they are subjected by the weight of the occupants of the cot, I desirably reinforce each of these rails with a 30 wrapper 11 of heavy sheet metal, which wrapper desirably extends around the end rail for more than its single periphery and desirably has one end of the bed bottom 1 clamped between the overlapping parts of 35 this sheet metal wrapper, so that this clamping will coöperate with the nails 12 in securing the bed-bottom to the end rail. Thus arranged, it will be evident from Fig. 6 that the metal wrapper 11 forms a tube which 40 in itself would have considerable stiffness and which reinforces the wooden end rail 3, so that I can secure the desired rigidity in the latter without using an excessively bulky or heavy rail. Associated with the 45 bed-bottom 1, I desirably provide a wrapper 13 of oilcloth or the like, which wrapper is made of a piece of fabric considerably wider and somewhat longer than the portion of the bed-bottom between the end rails, and 50 is secured substantially to the periphery of this portion of the bed-bottom. Owing to the greater dimensions of this wrapper 13, the latter will sag below the bed-bottom, somewhat after the manner of Fig. 5, thereby 55 affording an air space between the two. As this air space is considerably greater than the total of the air spaces in the interstices of several blankets, I readily obtain an effective thermal insulation greater than 60 would be secured by the use of a series of such blankets or pads, and without either the bulk or the weight of the latter. Then when the legs are folded against the end rails, the bed-bottom can be wrapped around 65 these rails as shown in Fig. 2, with the

wrapper 13 on the outside, so that this wrapper affords a waterproof covering which will keep the rain from reaching the bed of the cot. When I have thus rolled my cot in a compact bundle, I desirably employ the 70 same straps 6 and 7 for lashing the adjacent ends of the bed rails to each other, as shown in Fig. 2, thereby securing a rigid bundle which can freely be handled without the risk of its unrolling.

In erecting the cot for use in a car, the straps are loosened from the end rails and the fabric of the cot is unrolled with each pair of legs still folded against the adjacent end rail. Then each pair of legs is 80 unfolded part way and the legs are set approximately into their desired positions while diverging upwardly at acute angles. Next, I fasten the straps 6 and 7 to convenient portions of the car and draw up 85 these straps so as to pull the bed bottom 1 approximately taut. Then I increase this tension on the bed-bottom by spreading each pair of legs farther apart and thereby raising the end rails. In practice, the erection 90 as just described may be accomplished very quickly and by employing the change in angularity of the legs as one of the means of tensioning the bed-bottom, I am able to secure a taunt bed bottom and to hold the entire structure against swaying even when subjected to the strains of having the occupants climb into the cot or move around upon the latter. Moreover, by placing the legs with their tips in suitable positions, I 100 can readily keep both the legs and the end rails away from the upholstery of the car, so that I do not damage the leather as has been the case with cots heretofore provided for the same purpose. However, while I 105 have pictured and described my invention as embodied in a folding cot having forward legs adapted to rest upon the floor of the automobile, and having pivot members also affording the connections to the tensioning straps, I do not wish to be limited to these or other details of the construction here disclosed, it being obvious that the same might be modified in many ways without departing from the spirit of the appended claims. 110 For example, the forward legs 5 might be set upon the forward seat of the automobile after removing the cushion from the latter, as shown in dotted lines in Fig. 1. So also, I do not wish to be limited to a non-adjustable effective length of the cot, as the latter might readily be shortened by only partly unrolling the cot bed from one of the end rails; as for example, by permitting the bed 1 to remain wrapped once entirely 115 around the periphery of the end rail in Fig. 6.

I claim as my invention:

A folding cot comprising end rails, a bed bottom connected at its ends to said rails 130

respectively, a pair of eye bolts secured to each end rail, flexible tensioning elements secured at one end to respective eye bolts and adapted to have their other ends secured to fixed parts to initially tension the bed bottom, a supporting leg pivoted on each eye bolt and the supporting legs associated with each end rail being held in engagement with a support and in downward

convergence by the initial tensioning of the bed bottom by said flexible elements and operable by movement thereof to a position of parallelism to increase the tension of said bed body and flexible elements and dispose said bed body at a greater elevation with respect to the support. 10 15

Signed at Chicago, Illinois, May 3, 1919.
ISAAC S. PURCELL.
